UNITED STATES PATENT OFFICE.

WILLIAM A. YOUNG, OF NEW YORK, N. Y., ASSIGNOR TO WILLIAM A. YOUNG GASKET CORPORATION, OF NEW YORK, N. Y., A CORPORATION OF NEW YORK.

PACKING.

1,261,670.

Specification of Letters Patent. Patented Apr. 2, 1918.

Application filed October 31, 1917. Serial No. 199,471.

To all whom it may concern:

Be it known that I, WILLIAM A. YOUNG, a citizen of the United States, and a resident of the city of New York, Astoria, borough of Queens, in the county of Queens and State of New York, have invented a new and Improved Packing, of which the following is a full, clear, and exact description.

10 Among the principal objects which the present invention has in view are: to provide a packing of the character mentioned, the dimensions whereof may be readily altered; to provide a packing easily installed; 15 and to provide means for readily removing the packing from the shell.

Drawings.

Figure 1 is a perspective view of a shell 20 having applied thereto packing members constructed and arranged in accordance with the present invention, and showing in conjunction therewith a human hand with a knife in the act of severing the packing for removal of the shell;

Fig. 2 is an enlarged detail view of a packing member, the same being shown as disassociated from the shell.

Description.

30 As seen in the drawings, a packing member when constructed in accordance with the present invention has a twisted rope-like body 7. The body 7 is provided with loops 35 8 at both ends. The loops 8 are formed integral with the body 7 and are composed of two strands twisted or wrapped each upon the other while the body 7 is composed of four strands.

40 The packing herein shown is formed from loose fiber which in the initial step of the operation is twisted to form a wisp-like structure which when permitted recoils upon itself to form a crude rope. The crude rope 45 is made of two strands, which are then bent to form one of the loops 8. The portions of the rope adjacent the loops 8 are twisted more or less tightly to form the rope body 7. The short ends of the twisted strands 50 are turned between the crosses thereof adjacent the second formed loop and in the manner common in splicing rope. The double strand portion of the initially twisted

wisp is then bent to form the second loop 8, and that portion of the original double strand adjacent the free end thereof is wrapped or twisted about the body of that portion of the original strand adjacent the second loop. Care is exercised to have the two free ends of the original strand meet 60 adjacent the center of the body 7 where both free ends are threaded through and between the layers of the completed body, and in the end it will be found that a packing has been formed from wisps of rope fiber, the body 65 portion whereof is relatively heavier or thicker than the two eyelets at the ends thereof.

In service, as shown best in Fig. 1 of the drawings, the eyelets are disposed in a relatively flattened position to lie against the body of the object packed. The combined length of the body 7 and loops 8, is less than the circumference of the body being packed, when the same is in service. This provides 75 for the loops being normally separated. They are drawn together by lashings 9. The lashings employed when added to the thickness of the loops 8, equal in thickness the body 7, and in this manner form a relatively uniform thickness of packing material about the object packed, such as the shell 10 shown in the drawings.

When provided with packings constructed and arranged in accordance with the present 85 invention, the operation is as follows: If the object be, as shown in the drawings, a shell, the improved device is placed under the shell so that the shell rests on the body portion 7. The lashings 9 are then introduced through the loops 8 and are wrapped therethrough until the combined thickness of the loops and the lashing equals or approximates the thickness of the body 7. The lashings are then made fast in any suitable manner, the packing device being drawn 90 tightly about the shell in a manner to avoid accidental or easy dislodgment.

Arriving at the field where it is desired to remove the packed device, this is readily 100 accomplished by cutting the lashings in the manner indicated in Fig. 1 of the drawings, the knife being passed through the said lashing and between the ends of the loops 8. Care is exercised not to cut the loops 8, as 105 it is desired to preserve the packing, which

may be reshipped to the manufacturer to be reused.

Claims.

- 5 1. A packing comprising a rope-like body portion having loops integrally formed at the ends thereof, said loops having a relatively diminished quantity of material therein.
- 10 2. A packing comprising a rope-like body portion having loops integrally formed at the ends thereof, said loops being made with a fewer number of strands than said body portion to accommodate the use of a tying member.
- 15 3. A packing comprising a rope-like body portion constructed from strands of double

twisted fiber, said fiber being bent upon itself to form loops, the ends of each bent strand being added to the body portion to 20 make the thickness thereof one strand layer more than the thickness of said loops.

4. A packing comprising a rope-like body portion constructed from strands of double twisted fiber, said fiber being bent upon it 25 self to form loops, the ends of each bent strand being added to the body portion to make the thickness thereof one strand layer more than the thickness of said loops; and means for locking the free ends of the 30 strand portion last added to said body portion.

WILLIAM A. YOUNG.
